UNITED STATES PATENT OFFICE.

OLAF BJORKLUND, OF ST. PAUL, MINNESOTA.

HOT-WATER HEATER.

Application filed June 5, 1926. Serial No. 113,956.

This invention relates to a hot water boiler or a hot water boiler and furnace, and while the invention is applicable to various kinds of boilers, it particularly is designed for use 5 with such a hot water boiler or furnace as is used for domestic heating purposes.

It is an object of this invention, therefore, to provide a hot water boiler and furnace of simple and efficient construction and one 10 comprising a plurality of separable sections conveniently arranged so that a section can be quickly removed and replaced.

It is a further object of the invention to provide a hot water boiler and furnace comprising a lower section or ring having an annular water chamber formed therein and constituting the walls of a fire pot, together with a section having an upstanding portion disposed at its lower end in the fire pot and 20 forming a water chamber preferably annular in shape which communicates with the water chamber in said lower section.

It is still another object of the invention to provide a hot water boiler having a lower 25 section and an upper section, both having therein annular water chambers together with a section secured to the lower section at the rear portion thereof and having a water chamber therein communicating with the water 30 chamber in said lower section and having an upstanding portion preferably annular in shape, also having a water chamber therein communicating with the water chamber in the upper section.

It is more specifically an object of the invention to provide a hot water boiler and furnace having a base section, a lower section supported thereon, an upper section and a top section, all except said base section 40 formed with water chambers therein, together with an intermediate section having a water chamber therein communicating with the chamber in said lower section and with the chamber in said upper section, said 45 intermediate section having portions disposed substantially centrally in said furnace with its lower end in the fire pot of said furnace.

These and other objects and advantages of 50 the invention will be fully set forth in the following description made in connection with the accompanying drawings, in which like reference characters refer to similar parts throughout the several views and in 55 which:

Fig. 1 is a vertical section taken on line

1—1 of Fig. 2, a small portion of the smoke pipe and outlet pipe being shown in side elevation;

Fig. 2 is a horizontal section taken on line 60

2—2 of Fig. 1;

Fig. 3 is a horizontal section taken on line

3—3 of Fig. 1;

Fig. 4 is a horizontal section taken on line

4—4 of Fig. 1; and

Fig. 5 is a vertical section taken on line

5—5 of Fig. 1, all of said sections being

taken as indicated by the arrows on said

respective lines.

Referring to the drawings, a hot water 70 boiler and furnace is shown having a base portion 7. This base portion as shown is hollow, having bottom and side walls, and as shown in Fig. 2 is semi-cylindrical at its rear portion and substantially rectangular in 75 shape at its front portion. Said base member 7 has an opening 7^a in its front wall adapted to be closed by a door 8 hinged at one side by the pintles 9 and held in closed position by the keeper 10 at its opposite side, 80 said door being illustrated as having a handle 8^a adjacent its free end. The member 7 has an inwardly extending top wall or flange 7^b having an upstanding rib or flange 7^c cylindrical in shape adjacent its inner 85 edge. The flange 7^b inward of flange 7^c supports the grate member 11. While this grate may be of any desired type, it is illustrated as a plate having parallel slots or openings therethrough. Outward of the flange 7^c the 90 member 7 supports a section or ring 12 having spaced inner and outer walls forming a water chamber 12^a therebetween. The member 12 has a cylindrical flange 12^b at its upper end and a cylindrical shell or drum 95 13 fits about this flange and extends upwardly therefrom, being connected thereto by the headed and nutted bolts 14. The shell 13 has a rectangular opening in its front side about which extends a fire door casing 15 100 substantially rectangular in shape and having curved flanges at its inner side fitting over and being connected to the drum 13 by suitable rivets or bolts. The casing 15 has a fire door 16 hinged at its outer side on 105 the pintles 17 passing through alined lugs carried respectively on said door and casing. An intermediate section 18 is provided, having a lower laterally extending arm 18^a shown as substantially cylindrical in shape 110 and having a projecting curved terminal flange 18^b fitting against the inner wall of

the lower section 12 and connected thereto by the headed and nutted bolts 19. The arm 18^a is open at its end and registers with an opening in the inner wall of the section 12 so that the chambers therein are in communication. The member 18 has an upstanding portion 18^c and while this portion may be variously formed, in the embodiment of the invention illustrated it is shown as annular and comprising spaced annular walls forming an annular water chamber therein. The lower portion of the member 18 is disposed quite close to the grate 11 and is thus located in the fire pot of the furnace, the wall of which fire pot is formed by the inner walls of the section 12. The upper end of the portion 18^c of the member 18 has lugs 18^d projecting inwardly from its inner side and outwardly from its outer side, which lugs are alined with similar lugs 20^a projecting from the inner and outer sides of the annular portion 20^b of an upper section or ring 20. The upper end of the portion 18^c and the lower end of the portion 20^b are open so that the chambers therein are in communication as shown in Fig. 1. The section 20 also has an annular water chamber 20^c at its outer side communicating with the chamber in the portion 20^b through the arms 20^d as shown in Fig. 4, the ring 20 thus having the circumferentially spaced openings 20^e passing therethrough, said openings being illustrated as oblong or elliptical in form. The section 20 has a depending cylindrical flange 20^f surrounding the upper end of the drum 13 and connected thereto by headed and nutted bolts 21, said section thus resting on the members 13 and 18. A top section 22 is provided, having a top chamber 22^a therein and a surrounding downwardly extending chamber or leg 22^b at its outer side. The chamber 20^c and the chamber 22^b have alined holes at opposite sides thereof and a bi-conical connecting bushing 23 has its ends disposed respectively in said holes as shown in Fig. 5. It will be seen that the bushing 23 will be wedged down into the hole in chamber 20^c and the hole in the chamber 22^b will wedge down on top of the bushing. A tight joint is thus produced and the small crack left between sections 20 and 22 will be filled in with fire clay or similar material. A tight joint is thus produced and communication afforded between the chambers 20^c and 22^b. The downwardly extending chamber or leg 22^b is cut away at the front portion of the furnace to provide an opening extending into the space below chamber 22^a and above section 20 and said opening is adapted to be closed by a door 24 hinged at one side to the section 22 by the pintles 28. Inlet pipes 25 for water are threaded into bosses projecting from the lower section 12 at the sides thereof and outlet pipes 30 for steam or hot water projecting from bosses formed at op-

posite sides and at the top of top section 22. The top section 22 also has a plurality of circumferentially spaced openings 22^c extending therethrough which are also shown as of oblong or elliptical shape. A cylindrical flange 22^d extends upwardly from section 22 outward of the openings 22^c and a smoke pipe or connection 26 has an offset flange 26^a fitting over the flange 22^d and resting thereon. The pipe 26 is illustrated as extending upwardly and laterally in an inclined direction and the same has an opening 26^b at its forward side adapted to be closed by the hinged cleanout door 27 which also may be used as a damper.

In operation the boiler will be supplied with water through the inlet pipes 25, which water will substantially fill the water chambers in the sections 12, 18, 20 and 22. The fuel will be supplied through the fire door 16 onto the grate 11 and within the walls of the fire pot formed by the lower section 12. The chamber in the base 7 will form the ash pit. The fuel 29 as shown in Fig. 1 will extend about the lower portion of the section 18, this section as above stated thus being disposed with its lower end in the fire pot. The water in the section 12 and in the lower portion of section 18 will thus be heated directly from the fuel. The gases and products of combustion will pass upwardly in and about the portion 18^c of the member 18 within the drum 13 and will pass through the openings 20^e and 22^c to the smoke pipe 26 as indicated by the arrows. A very effective contact of these hot gases will thus be had with the various sections and the water will be very efficiently heated. The water can circulate from the section 12 up through the section 18 and into the sections 20 and 22. The hottest water and steam will be at the top of section 22 and will be taken off through the pipes 30. Any ashes or soot collecting on the members 20 and 22 may effectively be cleaned by operating through the opening closed by the door 24 and the top of the sections 22 can readily be cleaned of soot or ashes by operating through the opening 26^b. The ashes will of course be removed through the opening 7^a closed by the door 8. It will be seen that the various sections can readily be disconnected and any section thus readily removed and replaced. The intermediate section 18 will be most liable to be burned out, as it is disposed at its lower portion within the fire bed and this section can readily be removed by merely removing the bolts which connect it to the sections 12 and 20. Said section 18 is of a size so that it can be removed through the fire door of the furnace.

From the above description it is seen that applicant has provided a very simple and efficient form of hot water boiler and furnace. The device is conveniently made of separable

sections and these are arranged for ready removal and replacement and are constructed to give a very efficient heating action to the water. The parts of the furnace are quite simple in construction and are easily made and assembled.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claim.

What is claimed is:—

A hot water boiler and furnace having in

combination a lower section including an annular water chamber forming the walls of a fire pot, an annular shell section above said lower section and forming the furnace walls, a central annular section forming an open topped annular water chamber spaced centrally from said two first mentioned sections, said central chamber having an enlarged arm disposed directly within the fire pot of the furnace and removably connected and communicating with said first mentioned chamber, and an upper section having a central open bottomed annular water chamber releasably secured to said central open topped chamber to close the same.

In testimony whereof I affix my signature.
OLAF BJORKLUND.
